UNITED STATES PATENT OFFICE.

LOUIS Z. FERNÁNDEZ, OF SAN ANTONIO, TEXAS.

FLASH LAMP.

1,406,832.

Specification of Letters Patent. Patented Feb. 14, 1922.

Application filed August 9, 1921. Serial No. 490,950.

To all whom it may concern:

Be it known that I, LOUIS Z. FERNÁNDEZ, a citizen of Mexico, residing at San Antonio, in the county of Bexar, State of Texas, have invented certain new and useful Improvements in Flash Lamps; and I do hereby declare the following to be a full, clear, and exact description of the invention, such as will enable others skilled in the art to which it appertains to make and use the same.

This invention relates to flashlights for use in connection with photography.

The primary object of the invention is to provide a flashlight apparatus of such construction and character that operation of the shutter actuating apparatus of the camera will cause the flashlight powder or explosive to be ignited, whereby proper timing of both the camera shutter and flashlight apparatus is accomplished.

A further object of the invention is to provide flashlight apparatus of such character that it may be used in connection with various types of cameras successfully, and necessitating but minor changes in the operative mechanism for the camera shutter to render the flashlight apparatus applicable thereto.

30 A further object of the invention is to provide flashlight apparatus of such construction that in operating the same danger of premature explosion is obviated.

35 A still further object of the invention is to provide a flashlight apparatus as above characterized and for the purposes set forth which is of such construction that predetermined quantities only of the explosive powder is delivered to the point of ignition.

40 Further and particular objects are to provide a device of the character stated and for the purposes specified which shall be of comparatively simple construction, easy and positive of operation, which is composed of but few simple and readily assembled parts, the various parts being so constructed and arranged as to minimize the opportunity for wear or derangement, and which will prove thoroughly practical and efficient in use.

50 With these and other objects in view, the invention consists of the features of construction, combination and arrangement of parts, hereinafter fully described and claimed, reference being had to the accompanying drawing, in which:—

Figure 1 is a front elevation of flash-

light apparatus constructed in accordance with the invention and illustrating the same in inoperative position,

Figure 2 is a rear elevation of the device 60 as shown in Figure 1,

Figure 3 is a vertical transverse sectional view taken through the improved flashlight apparatus with the parts in the position in Figure 1,

Figure 4 is a detail view taken longitudinally through the tray of the flashlight apparatus and illustrating the igniter in operative position,

Figure 5 is a vertical sectional view taken 70 through the charging tube,

Figure 6 is a detail view taken through the tube supply container and illustrating the manner in which the explosive powder is fed to the tube, and

Figure 7 is a view similar to Figure 6 and showing the charging valve in the act of delivering a charge of powder to the conveyor.

Referring now more particularly to the 80 drawing, 10 indicates the flashlight board or deflector, which is supported upon a standard indicated generally at 11, the said standard in the present instance including a base 12 and telescopic sections 13; the latter 85 permitting of vertical adjustment of the board. The sections of the tubular standard are maintained in the desired position of adjustment by means of the set screws indicated at 14.

The board or deflector 10 may be made of any suitable material and may be of any desired size, and is provided upon its forward face with a tray 15 formed preferably of metal, the said tray extending transversely across the board 10 intermediate the ends of the latter and having its edges upturned as at 16. The lower face of tray 15 is provided with a downwardly extending stud for engagement within the internal 100 threaded upper end of the uppermost of telescopic sections 13.

The apparatus used in connection with the above described board and stand includes a tube 17 arranged at the rear of 105 the standard and in spaced parallel relation preferably to the standard 11, being supported by the latter through the instrumentality of brackets 18 carried by one of the standard sections and projecting outwardly therefrom. Set screws 19 in the said brackets hold the tube 17 in proper

position within the brackets. The upper end of tube 17 curves forwardly as at 20 toward the board or screen 10, and the extremity of this curved portion protrudes 5 through a suitable opening in the said board, as shown. This forwardly projecting extremity of the tube is closed by a cap 21, the latter being held normally over the end of the tube by a spring 22.

10 Communicating with tube 17 near the lower end thereof is a delivery tube constituting a short tubular section indicated at 23. This delivery tube inclines downwardly toward its juncture with tube 17, and the 15 outer end of tube 23 is designed to receive the end of a flask or container 24' of explosive powder, such as that commonly used in flashlight photography. The container 24' may comprise a bottle having a threaded 20 neck to threadedly engage and snugly fit within the end of the delivery tube 23, thus enabling the container to be readily applied and removed from the delivery tube.

The tube 23 is provided with a valve oper- 25 able so as to permit only predetermined quantities of the explosive powder to be delivered to tube 17. This valve includes a pair of plates 24 and 25 arranged in spaced parallel relation and movable as a unit, the 30 said plates passing through suitable openings provided in the delivery tube 23. The plate 25 is relatively short and when moved to its proper upward position is withdrawn from the passage in the delivery tube 23. 35 The plate 24 is considerably longer than plate 25, and is provided with an opening 26 adapted, when the plate is lowered properly, to align with the passage of tube 23. The construction and operation of the 40 valve is such that when "raised", the powder within the tube 23 will be prevented from flowing into tube 17 by the lower portion of plate 24, such plate portion obstructing the 45 passage of the powder. When, however, the valve is "lowered", plate 25 will pass across the tube in the rear of plate 24, obstructing powder in the rear of the said plate, while the opening 26 will move into register with the interior part of the tube and the powder 50 contained between plates 24 and 25 will be allowed to pass from tube portion 23 into the main tube 17. The quantity of powder contained between plates 24 and 25 will be sufficient to constitute a proper charge. The 55 valve is held normally in raised position by a contractile spring 27, the said spring being connected at one end with the valve and at its other end with a hook or stud 28 on tube 17.

60 The means for conveying the charges of explosive powder to the tray or pan 15 includes a cup having its upper open end of substantially the same diameter as the interior of tube 17, and this cup is connected 65 to a disk or plate 29 of equal diameter with

the interior of the tube. A flexible member such as a spring 30 connects the cup and disk with the upper end of an operating rod 31, the lower end of the said rod passing out through the restricted lower end of tube 17 70 and being provided with a hand grip 32.

The lower end of plate 24 of the valve is provided with an offset finger 33 which extends to the interior of tube 17 through a slot 34 therein, and lies in the path of disk 29. 75 When the rod 31 is pulled to its lowest limit, disk 29 will engage finger 33 and move the same downwardly, so as to operate the valve to discharge a quantity of the explosive powder into the tube 17, and as this operation of 80 the valve is not completed until cup 28' is below the juncture of tube portion 23 with tube 17, the powder discharged by the valve will gravitate into the cup 28'. After this operation has taken place, the rod 31 is moved upwardly, the cup 28' at the upper end thereof carrying its charge of powder up tube 17 and around the curved portion 20, this 85 passage around the curved portion being permitted by reason of the flexible connection between the cup and the rod proper. When the cup has become inverted and at the free end of the curved portion of tube 20, the valve or cap 21, either by reason of 90 the weight of the powder which has been deposited thereon from cup 28', or by means of pressure of cup 28' against the same, will open, and the charge of powder will be deposited upon tray 15. As soon as the powder has passed from the tube end, spring 95 22 will move cap 21 back to closed position.

The means for igniting the explosive powder thus deposited upon tray 15 may be described as including a tubular arm 35, having an angularly disposed end 36, and being secured preferably at the juncture of the angular end with the main portion of the tube to a rod 37 disposed transversely of tray 15 at one end thereof and mounted in suitable 105 bearings in the flanges 16 of the said tray. 110 The tubular arm 35 carries a tank or container 38 for an inflammable liquid; such as gasoline, and a wick contained within the arm and angularly bent portion protrudes beyond the end of the latter. The arm is so 115 balanced that the tank end thereof is normally lowered, so that the free end of angular extension 36 lies within a snuffer indicated at 39. This snuffer is secured to the forward face of board 10, and it is apparent 120 that any flame at the end of the angular arm will be extinguished when the said end passes into the snuffer.

It will be understood that when the tank 125 end of arm 35 is elevated, the said arm rocking upon its shaft 37 will cause the free and ignited end of the angular portion 36 to move down into such position that the flame therefrom will ignite the explosive powder which has been deposited in the tray, as 130

above described. Within the ignited end of the torch, sparking points 39' are arranged upon the forward face of board 10 and in the path of travel of the wick end of arm 5 portion 36. It is obvious, therefore, that as the end of the arm wipes across these sparking points, the spark then set up will ignite the torch. The sparking points are supplied with electric energy from a source such as 10 the storage or cell batteries 40 located within base 12 of the standard, and wires 41 leading therefrom connect with the sparking points. If desired, a switch such as shown at 42 may be provided in the circuit so that 15 the latter may be opened or closed as desired.

That end of tray 15 which supports the torch member is provided with a downwardly extending portion 43, upon which is secured an air pump 44 of conventional form, 20 and which not only governs the movements of the torch member but also opens or closes the switch 42. This pump contains a piston (not shown) to which is secured the lower end of a piston rod 45, the latter being pivoted at its upper end to the rear end of a rock lever 46. Rock lever 46 is mounted upon a standard 47 carried by tray 15, and the forward end of the same carries a roller 48 resting upon a plate 49 secured to pintle 25 rod 37 of the torch member. The piston rod 45 carries an arm 50 constituting a control arm for switch 42. The pump 44 receives air from a flexible tube 51 connected 30 with the shutter operating bulb of the 35 camera (not shown).

In operation, the standard carrying the board 10 and its discharge apparatus is positioned in proper relation to the subject to be photographed. The air pump 44 is connected with the actuating mechanism of the 40 camera shutter. In the present instance, the invention is described for use in connection with bulb actuated shutters, but it will be understood, of course, that the piston rod 45 may be caused to be moved by other shutter operating means. The photographer pulls down upon rod 31 until the cup at the upper end thereof has received its charge, whereupon the rod is moved upwardly so as 45 to deposit the charge upon tray 15. When the shutter operating bulb is pressed, the camera shutter will not only be caused to open but the piston within the pump cylinder 44 will be raised, causing piston rod 45 50 to move upwardly, closing the circuit through the sparking mechanism, and causing the roller 48 to press down upon the inclined plate 49 secured to the flexible rod 37 of the torch apparatus. This causes the 55 wick end of arm 36 to move out of the snuffer and to brush across the sparking points, thus becoming ignited, and further downward swinging movement of the arm 36, caused by continued movement of rock lever 46, will 60 cause the ignited torch to light or set off the 65 charge of powder upon the tray 15. When the bulb of the camera has been released, the unbalanced member 35 will swing back to normal or inoperative position, causing the torch to become extinguished, and the circuit 70 through the sparking apparatus will be broken.

While the above is a description of the invention in its preferred embodiment, it will be understood that various changes in 75 the minor details of construction and arrangement of parts may be made without departing from the spirit of the invention as defined by the claims.

Having thus fully described my invention, I claim:

1. In a flashlight apparatus, in combination with the shutter actuating mechanism of a camera, a holder for an inflammable charge, a torch, sparking points to ignite the 85 torch, and means operated upon actuation of the shutter operating mechanism for energizing the sparking points and for moving said torch into contact with said inflammable charge. 90

2. In a flashlight apparatus, a holder for an inflammable charge, a torch movable toward and away from said charge, sparking points in the path of said torch, and means for moving said torch in one direction and 95 for simultaneously closing a circuit through said sparking points.

3. In a flashlight apparatus, a tray adapted to hold an inflammable charge, a pintle carried by said tray, a torch secured to said 100 pintle, a snuffer to limit the movement of said torch in one direction, an air pump, and a rock lever operable by said pump for rocking said torch upon its pintle in one direction. 105

4. In a flashlight apparatus, a board, a tray secured to one face of said board and adapted to hold an inflammable charge, a pintle carried by said tray, a tubular arm secured to said pintle, a source of fuel supply 110 carried by said arm, a torch connected to said arm, sparking points in the path of movement of said torch, an air pump, a lever governed by the movement of said air pump for moving said torch toward said inflammable charge, a switch in the circuit of said 115 sparking points, and an arm governed by operation of said pump for closing or opening said circuit.

5. In a flashlight apparatus, a charging 120 tube, a rod movable in said tube, a cup carried by said rod, a source of supply for said tube, and means operable when said cup is disposed below said source of supply for establishing communication between the supply and said tube. 125

6. In a flashlight apparatus, a charging tube, a cup movable within said tube, a source of supply for said tube, and means governed by the movement of said cup for 130

establishing communication between said source of supply and said tube.

7. In a flashlight apparatus, a charging tube, a source of supply for said tube, a valve controlling said source of supply, and a cup movable within said tube and governing the movements of said valve.

8. In a flashlight apparatus, a charging tube, a tube section communicating with the said charging tube, a valve in said tube portion governing the quantity of material to be delivered to said charging tube, a finger on said valve extending into said charging

tube, and a cup movable within said charging tube and adapted to engage said finger. 15

9. In a flashlight apparatus, a standard, a board carried by said standard, a tray, a charging tube communicating with said tray, means within said charging tube for determining the quantity of material to be 20 deposited upon said tray, a torch swingingly mounted upon said tray, and means for moving said torch into contact with material deposited on said tray from said tube.

In testimony whereof, I affix my signature. 25
LOUIS Z. FERNÁNDEZ..
